UNITED STATES PATENT OFFICE.

WALTER S. HAVEN, OF RACINE, WISCONSIN.

STEAM OR VAPOR HEATING SYSTEM.

1,406,556.

Specification of Letters Patent. Patented Feb. 14, 1922.

Application filed February 2, 1916, Serial No. 75,791. Renewed August 16, 1921. Serial No. 492,873.

To all whom it may concern:

Be it known that I, WALTER S. HAVEN, a citizen of the United States, residing at Racine, in the county of Racine and State

5 of Wisconsin, have invented certain new and useful Improvements in and Relating to Steam or Vapor Heating Systems, of which the following is a specification.

This invention relates to certain improvements in steam or vapor heating apparatus; and the objects and nature of the invention will be readily understood by those skilled in the art in the light of the following explanation of the accompanying drawings illustrating what I now believe to be the preferred embodiment or mechanical expression of my invention from among other forms, constructions, arrangements, and combinations within the spirit and scope thereof.

10 20 An object of the invention is to provide improved means in (so-called) vacuum steam heating systems for maintaining a negative pressure pull or an air exhausting action on the radiator system to compensate for air leakage by utilizing the pressure reducing action of a column of liquid descending in a closed passage system and by repeatedly using the same body of liquid to reduce waste of liquid to the minimum.

25 30 A further object of the invention is to provide a steam or vapor heating system with means for maintaining a minus pressure pull on the radiators by utilizing the pressure reducing and air expelling action of a descending column of liquid passing successively from chamber to chamber of a series of closed chambers at different elevations.

35 40 A further object of the invention is to provide a steam or vacuum heating system wherein the liquid employed to secure negative pressure can be utilized over and over again in maintaining the desired air exhausting action or negative pressure pull on the radiators or radiator system.

45 50 A further object of the invention is to provide a steam or vapor heating plant with improved means for automatically and periodically draining a closed chamber in air exhausting communication with a radiator system to exert negative pressure pull on said radiator system.

55 A further object of the invention is to provide a liquid draining system for maintaining negative pressure pull or air exhausting action on the radiator system of

a steam or vapor heating plant by causing the draining means to operate periodically through the provision of an automatic valve mechanism.

60 A further object of the invention is to provide a draining system wherein liquid is successively drained from one closed chamber to another of a series of such chambers to successively fill said chambers 65 to expel air therefrom and to empty said chambers to produce air exhausting action on the radiators of a steam or vapor heating plant.

A further object of the invention is to 70 provide improved tank or chamber draining means involving an automatic valve device and a siphon.

A further object of the invention is to 75 provide means for filling and emptying tanks or chambers involving an improved valve mechanism.

A further object of the invention is to provide certain improvements in combinations of parts and features and in constructions and arrangements with the end in view of producing a highly efficient and advantageous steam or vapor heating plant.

80 85 A further object of the invention is to provide a steam or vapor heating plant with liquid operated means for maintaining negative pressure pull on the radiator system embodying devices for automatically cutting off the liquid supply flow when the pressure in the radiator system is plus and for automatically establishing or starting the liquid supply flow when the steam pressure in the radiator system falls to approximately minus pressure.

90 95 A further object of the invention is to provide a steam condenser in the air pipe line between the radiator system of a steam or vapor heating plant, and the liquid operated means for maintaining negative pressure pull on the radiator system, to prevent 100 passage of steam through the pipe line into said means, should steam pressure for any reason be long continued.

105 The invention consists in certain novel features in construction, and in combinations and arrangements as more fully and particularly set forth hereinafter.

Referring to the accompanying drawings:

110 Fig. 1, diagrammatically illustrates a portion of a steam or vapor heating system including my present improvements.

Fig. 2, is a detail view of valve and siphon draining means that can be employed therein.

Fig. 3, diagrammatically illustrates a modification of the liquid tank and drainage means for establishing minus pressure pull on the radiator system.

Fig. 4, is a detail view somewhat diagrammatically illustrating means that might be employed to start and stop the liquid supply flow to the top tank of the vertical series of small tanks.

Fig. 5, is a detail view of a modification.

Fig. 6, is also a detail view of another modification.

In the drawings, portions of the radiators 1, of the radiator system of a steam or vapor heating system, are shown.

It will be understood of course, that these 20 radiators are merely diagrammatically illustrated to indicate any suitable heat radiating elements or units that are connected in any suitable manner with a steam or vapor generator to receive steam or vapor therefrom, 25 preferably so that negative or minus pressure existing in said radiators will be communicated through a closed steam or vapor supply pipe system of said generator to draw vapor therefrom into the radiators.

30 Any suitable pipe line or air line 2, is provided to receive the air from the radiators and through which negative or minus pressure can be maintained in the radiators. This air or exhausting pipe line is diagrammatically illustrated and can be provided with any desirable controlling valves, cut offs, or the like, such for instance, as are commonly employed in so called vacuum or vapor heating systems. This air line usually 35 consists of a closed pipe line coupled into the outlet or discharge ends of all the radiators to receive the air therefrom and is provided with any suitable arrangement of check valves to prevent back flow of pressure or air into the radiators yet to permit free outflow of air therefrom, and with 40 thermostatic valves 1', to prevent outflow of steam from the radiators, and with a final air discharge to atmosphere which final discharge is equipped with means to prevent back flow of air.

Between the radiators and said final discharge to atmosphere, said air line is provided with means for producing negative or 55 minus pressure in said line and the radiators, comprising a series of tanks, compartments or other chambers to be successively filled with liquid to force air from such chambers and to be successively drained 60 from one to the other under such conditions as to create negative pressure therein and thereby exert air exhausting pull on the radiators through said air line.

In the particular example illustrated, I 65 show a vertical series composed of any suit-

able number of elevated closed tanks, chambers or compartments, 3, 3^a, 3^b, 3^c, arranged in different horizontal planes so that liquid will flow from the highest tank 3, to the next tank 3^a, below and so on down from tank 70 to tank throughout the series, so that each tank will be approximately filled and then emptied.

The standpipe 2^a, of the air line extends up beside this series of tanks and is separately connected with the tanks through the medium of branch pipes 2^b, one for each tank. The standpipe is in open communication with the top of the interior of each tank through a branch 2^b, for free flow of air from the air line into the tanks, but is closed against back flow from tank to air line by check valves 2^c, in said branches 2^b.

The air discharge from these tanks can be taken care of in whole or in part by an off-take standpipe 4, separately connected with the tanks through the medium of branch pipes 4^a, one for each tank, opening into the top of the interiors thereof and each equipped with a check valve 4^b, to permit free flow of air from the tanks into the standpipe 4, but to prevent back flow from the standpipe to the tanks.

At its lower end, this standpipe 4, has a discharge 4^c, to atmosphere, which preferably constitutes the final air discharge or outlet to atmosphere for the entire air line from the radiators. This outlet to atmosphere is provided with any suitable means to prevent inlet of air to the standpipe 4, although in the example illustrated, I show liquid seal 4^d, for this purpose, with the outlet end of standpipe 4, also preferably equipped with freely downwardly opening check valve 4^e, to prevent upflow of water from the water seal under conditions that might possibly arise.

In the example illustrated, and so far described, the air line in reality includes the standpipes 2^a, and 4, and their branch pipes as well as the series of tanks, as the air flows therethrough on its way from the radiators to the final discharge to atmosphere at liquid seals 4^d, and 6^d.

Any suitable means can be provided for 115 supplying the water or other liquid for carrying on the negative pressure producing action resulting from the successive filling and emptying of the tanks hereinbefore mentioned, although in the example illustrated, I show a water supply pipe 5, from any suitable source of water under pressure (such as a municipal water supply system) from which water is supplied for maintaining a normally approximately constant flow 120 of water into the uppermost tank 3, of the series. This pipe 5, is provided with shut off valves, for entirely cutting off and for controlling the rate of flow of water into the tank system.

I frequently prefer to connect the pipe 5, so as to discharge into the lower part of the interior of a relatively large closed tank or chamber 3', elevated above the series of tanks mentioned, and to discharge the liquid from this large tank through the series of tanks. Where this large tank is employed, the standpipe 2^a, opens into the upper part of the interior of said tank and is equipped 5 with a check valve 2^e, arranged to freely open toward said tank but to prevent back flow of air from said tank. The standpipe 4, also opens into the top of the interior of said large tank to carry off air therefrom 10 and is equipped with check valve 4^e, arranged to freely open for passage of air from the tank but to prevent back flow from said standpipe to the tank.

This large tank is provided with a depending drainage pipe 3'', from the lower part 20 of its interior to the relatively small tank 3. This drainage pipe 3'', discharges into the lower part of the interior of tank 3, and its outlet in said tank is closed against back flow of air by a water seal 3^d. The pipe 3'', is of small capacity so that the flow of liquid from large tank 3', will be very slow, and this pipe is provided with cut off valve 3^g, for completely closing said pipe as when the 25 large tank is cut out of the air line, or for regulating the flow of water therethrough when the tank 3' is in use.

The standpipes 2^a, and 4, can also be provided with cut off valves 2^g, and 4^g, and the 30 pipe 5, with cut off valve 5^g, whereby the large tank can be cut out of the air line if so desired. In that event, the branch pipe 5', from the water supply pipe 5, can be utilized 35 for filling the tank 3. This branch 5', is of relatively small capacity to provide a very slow passage of water into tank 3, and is provided with cut off valve 5^a, for regulating the flow of water to said tank, and for entirely cutting off said branch as when the 40 large tank is included in the system, and the tank 3, is supplied with water therefrom.

In Fig. 3, I show an air exhausting system comprising the series of tanks 3, 3^a, 3^b, 3^c, with the water supply pipe 5, 5', discharging 50 into the tank 3, and omitting entirely the large upper tank 3', and its connections, the systems of Figs. 1 and 3, being otherwise the same.

A pipe 6, is provided for draining the uppermost tank 3, into the next tank 3^a, below, for filling said last mentioned tank and expelling the air therefrom, and another pipe 6^a, is provided for draining the water from tank 3^a, into the next tank 3^b, and another pipe 6^b, 55 is provided for draining the water from tank 3^b, into tank 3^c, while a fourth pipe 6^c, is provided for draining the last tank in the series. This pipe 6^c, preferably discharges the water to atmosphere through 60 the medium of a water seal 6^d, from which

the overflow can pass any suitable drain or offtake. The water seal 6^d, is provided to prevent any possibility of back flow through pipe 6^c, and said pipe is also preferably equipped with downwardly opening 70 check valve 6^e, to prevent upflow of the liquid from the seal.

The discharge ends of the drain pipes 6, 6^a, 6^b, in the tanks 3^a, 3^b, and 3^c, are preferably closed against up flow of fluid therein 75 and for this purpose, I show water seals 6^f, arranged on the floors of said tanks.

Each small tank of the series is provided with suitable means to prevent drainage of liquid from the tank while the tank is being 80 filled and the air is being expelled therefrom, and to start the operation of draining the liquid from the tank into the next tank below or into the water seal 6^d, when the tank has been filled with liquid, and by this draining or emptying process to create minus or negative pressure in the standpipe 2^a. The means I prefer to employ are automatic in action to automatically close the drainage outlet from each tank when the liquid has 85 been drawn therefrom, and to automatically open the drainage outlet and start the down flow of liquid from the tank when the tank has been filled with liquid. Each tank will thus be periodically automatically filled with 90 liquid and then emptied, the liquid passing down successively from tank to tank, and each tank as it is filled discharges air and each tank as it is emptied draws air from the radiators through standpipe 2^a, or from 95 the tank above, or from both sources.

In the particular example illustrated, I provide each tank 3, 3^a, etc., with a depending or bottom well 8, into which the liquid in the tank is adapted to drain, and the offtake or drain pipe 6, 6^a, or 6^b, of the tank has its inlet end arranged in the bottom portion of this well to carry off the liquid therefrom. The upper end of each said drain pipe is preferably formed with a goose neck 6' so 100 arranged that each drain pipe constitutes a siphon with its long leg depending to and discharging into the next tank below and with its short leg at the upper end of the pipe and having its inlet end near the bottom of the interior of the well 8.

This well may be of any desired shape and capacity with respect to the chamber or tank that drains into the well. The upper chamber or tank in this connection supplies 105 the necessary volume of water to prime the siphon.

The floor or bottom of each tank is formed with a vertical port or passage for the flow of liquid from the body of the tank into the well and this port is surrounded by a preferably tapered or depending valve seat 9.

The flow of liquid through this port from the interior of the tank is controlled by 110 any suitable valve, such as ball valve 10, 130

adapted to close down on the seat to stop the flow when the tank is filling and adapted to rise from the seat and permit the flow after the tank has been filled. This ball valve, if so desired, can be provided with an upwardly extending stem or valve rod 11, to the upper end of which is fixed a float 12, and if so desired, guides 13, carried by suitable uprights can be provided, through which said stem is freely slideable vertically and by which it is maintained in vertical position.

The float 12, is of such size or lifting power that it will lift and unseat the valve 10, when the liquid fills the tank and acts on said float. Said valve is preferably composed of a hollow ball of comparatively light weight of less specific gravity than water so that the valve will rise from its seat when subjected to the lifting action of a body of water filling the well. The valve, on the other hand, is of such weight and formation as to seat and close the outlet or port in the bottom of the tank when the well is free of water, or when the water level therein is below the valve, and so as to be maintained on its seat in port closing position by the static pressure of the water in the tank. The buoyant quality of the float prevents the valve 10, from prematurely reseating under the suction or drawing action of the body of water flowing through the port from the tank.

An air escape and drain pipe 6", is provided for each well 8, with its open upper inlet end in the upper part of the well in a horizontal plane above the horizontal plane of the valve seat 9, and with its lower end opening into the long leg of the siphon (into pipe 6, 6^a, 6^b, or 6^c) a distance below the horizontal plane of the inlet end of the siphon so as not to interfere with the proper operation of the siphon. The combined capacities of pipe 6", and the siphon is less than the capacity of the port 9, and the horizontal plane of the valve seat is below the horizontal plane of the lowest portion of the curve of the goose-neck. When the valve 10, is elevated by its float, the well is rapidly filled and the air is driven therefrom through pipe 6", and into pipe 6, 6^a, etc., into the tank below or through pipe 6^c, to atmosphere. When the well is filled the water drains therefrom by gravity through the drain pipe 6", and through the siphon, until the water level falls to a point where the siphonic action must be depended on to drain the well as hereinafter explained.

When the tank is approximately filled, the valve 10, is automatically unseated and water rushes from the tank into the well in greater volume than can be carried off by the drain pipes 6', 6", and hence the well becomes completely filled although water is draining off through said pipes 6', 6". The siphon is

primed by this complete filling of the well as the water level is then above the highest part of the siphon and the siphon is completely filled and hence begins its siphonic action in draining water from the well.

70

When the body of the tank is emptied, the valve settles with the falling water onto its seat and closes the outlet port, and the water then partially filling the well is drawn or drained therefrom by the gooseneck-drain pipe which then begins to perform the functions of a siphon to lift the remaining water from the well which if allowed to remain in and filling the well up to the valve seat, would prevent the valve from entering and maintaining its seat when the water begins to again fill up the tank. The siphon is primed by the water filling the well and completely filling the short leg and goose neck of the siphon, from the chamber or tank above, the water being thus forced from a higher level through the goose neck of the drain pipe to the tanks below. After the tank has become empty, the siphon action of the drain pipe continues until the well is 90 drained. Meanwhile, the valve 10, has become seated both by gravity and the suction action of the water draining from the well.

80

If so desired, an air escape and overflow pipe 14, as shown by Figs. 5 and 6, can be provided for each of the series of tanks 3, 3^a, etc., having its open upper end arranged in the upper part of the interior of the tank and its lower discharge end arranged at the bottom of the interior of 100 the well of such tank and provided with a liquid seal 14' to prevent upflow of air through the pipe.

90

When these pipes 14, are employed, water can drain therethrough by over-flow into 105 the wells when the tanks are filled in the event that the floats 12 of Fig. 5, fail to elevate the valves 10, or if the float is not employed, or in the arrangement disclosed by Fig. 6, the water overflows through these 110 pipes 14 to operate the floats and unseat the valves 10. Also, as the tanks fill, air can pass therefrom through pipes 14, into the wells, from which it flows through pipes 6" and 6, 6^a, etc., to the tank below or 115 through pipe 6^c, to atmosphere. The air expelled from the tanks as they are filled, will follow the path of least resistance, either through pipes 4^a, and 4, to atmosphere, or the inside course through pipes 14, 120 6', 6 or 6^a, etc., from tank to tank and finally from the system through pipe 6^c. In fact, where the pipes 14, and 6', or their equivalents are employed to provide an inside course for the air through the tank system, 125 I can dispense with the air outlet pipes 4^a, and 4, and pipe 6^c can form the final air discharge as well as the final water discharge from the air exhausting system.

Also, should the lower tanks of the series 130

when being emptied, suck or draw air from the upper tank or tanks rather than through their suction inlet pipes 2^b, the air exhausting action on the radiator system will be 5 the same as though each tank exerted its pull through its branch pipe 2^b, as contemplated. This might occur in case of the employment of overflow pipe 14.

In the drainage valve arrangement of 10 Fig. 6, the valve 10, is provided with a lift float 12, arranged in the well and the well is filled to lift the float and consequently the valve from its seat through the pipe 14.

To prevent the flow of water through the 15 outlet port from the tank, when the valve is elevated from its seat, from forcing down the float and seating the valve, I provide a shield or horizontal portion 12'', between the outlet port from the tank and the float 20 to receive the impact of the falling water. This shield provides vertical water passages or holes 12^a, at its edge portion remote from the float, to permit passage of water to the portion of the well containing the float and 25 to permit the water to fill the well as hereinbefore described. Otherwise the operations of the valve and float and of the siphon and drainage pipe 6'', are as hereinbefore described.

30 The drain pipe 14, or the float controlled valve, provide for the preliminary filling of the well to prime the siphon, and to release the valve while the siphon serves to finally drain the well to permit proper seating of the valve, although I do not wish to limit all features of my invention to the particular draining means involving a valve and siphon.

It is desirable to prevent the passage of 40 steam from the radiator system into the standpipe 2^a, and the liquid tanks, and hence I can employ any suitable construction or arrangement of steam condenser in the air pipe line from the radiator system. For 45 instance, I more or less diagrammatically show a steam condensing coil or other radiator c, located between the radiator system and the standpipe 2^a, to assure the condensation of all steam that might leak from the 50 radiator system into the air pipe line.

While the steam or radiator system is under plus pressure, i. e. when the steam pressure is above that of the atmosphere, there is no necessity of filling and draining the 55 tanks to expel and draw in air for then air leakage into the radiator system does not occur. Hence, I preferably provide means to cut off the flow of water into the tank 3, when plus pressure exists in the radiator 60 system, or in the air pipe line standpipe 2^a, and thereby avoid waste of water. In the particular example illustrated, I provide a sliding or reciprocatory cut off valve 16, in the water supply pipe 3'', (Fig. 1) 65 or 5', (Fig. 3) to tank 3, operated by a

lever 17, to open and close said pipe. This lever is operated or actuated, to stop or start the flow of water, by any suitable pressure operated means connected with the radiator system. For instance, I show flexible 70 diaphragm 18, having a rod 19, fixed thereto and pivotally joined to lever 17. The diaphragm forms the flexible wall of a pressure chamber 21 connected by air pipe 20, to the radiator system, through standpipe 2^a, 75 and the air line 2. Plus pressure in the radiator system will elevate the diaphragm and close the valve 16, and stop the flow of water to tank 3. The instant the pressure falls in the radiator system, to a pre- 80 determined point at which the pressure device is set or adjusted to open valve 16, the flexible diaphragm drops or moves inwardly and starts the flow of water to set up the minus pressure producing action of the 85 liquid in the tanks.

However, I do not wish to limit all features of my invention to this means for automatically starting and stopping the flow of 90 the supply liquid.

In considering the operation of the system described, we will start with the radiators cold and containing air at atmospheric pressure, and the large and small tanks empty and in open communication with the radiators, and with the cut-off valves 5^a, 5^b, and 3^c, closed and the cut-off valves 2^e, 4^e, open. The furnace is then started to generate steam or vapor in the boiler which as the pressure rises will enter the radiators and drive the 100 air therefrom into the air line. When the pressure has reached the desired point in the radiators (thermostatic valves 1' and condenser c, preventing flow of steam from the radiators into the air line) the air has been 105 driven therefrom into the various tanks and when the pressure in said tanks exceeds atmospheric pressure the dead air will escape through the water seal 4^d, to atmosphere at the discharge end of standpipe 4. When 110 the dead air has thus been driven from the radiators, or at any other convenient time, valve 5^b, in the water supply pipe is opened and water under pressure is admitted to the large tank 3' to expell the air therefrom 115 through standpipe 4. When said tank is full, the valve 5^b, is closed, and a comparatively large supply of water is thus provided in the tank 3', to operate the air exhausting system for a considerable length of time, say 120 for twenty four hours, although this depends on the adjustment of the means controlling the rate of flow or drainage from the tank, and on the capacity of the tank, all of which can be arranged and varied to suit 125 particular instance.

When the large tank is thus provided with the desired supply of water, the valve 3^e, is opened to permit a slow leakage of water 130

through pipe 3'', and into the small tank 3. The withdrawal of water from the closed tank 3', causes a decrease in pressure therein and a consequent air exhausting pull on the radiators through the medium of standpipe 2^a, and pipe line 2.

The small tank 3, is gradually filled by said slow flow of water through pipe 3'', and air is thereby driven therefrom through 10 branch 4^a, and the standpipe 4, except as modified by the employment of overflow pipe 14. When the tank 3, is filled, the water is automatically emptied therefrom to exert air exhausting pull through branch 2^b, 15 and pipes 2^a, 2, on the radiators, and to fill tank 3^a, and drive the air therefrom, and so on down through the series of small tanks as hereinbefore described. The small flow of water through the drain pipe 3'', is constant 20 and continuous during the operation of the air exhausting system, to compensate for air leakage into the radiators and pipe line. Whenever the supply of water in the large tank is exhausted, the valve 5^b, in the water 25 supply pipe is opened to again fill said tank.

The small tanks of the series are usually of approximately the same capacity so that the same body of water will pass from tank to tank expelling the air from each tank in 30 succession and then creating minus pressure in each tank in succession so that the same body of water is used over and over again to expel air from the air line and to draw air from the radiator system into the air line 35 and this operation is periodically and automatically repeated in each tank so long as the slow flow of water through pipe 3'', continues.

By thus using the same body of water over 40 and over again to successively produce air exhausting operations, economy is effected in the use or waste of municipal water, and furthermore an exceedingly efficient air exhausting system for heating plants is produced 45 possessing all of the advantages of the system of my pending patent application filed March 9, 1915, Serial Number 13291 with additional features of advantage and utility.

50 In the construction illustrated by Fig. 3, the tank 3', and the drainage pipe 3'', are omitted together with the extensions of pipe 5 and standpipes 2^a, and 4 to said tank, and the supply of water is delivered direct by 55 pipe 5, 5', into the small tank 3, so that the operation of the system is the same as that hereinbefore described except with respect to the large tank 3'. The pipe 5' and the cut off valve 5^a, control the constant flow of 60 water into the tank 3, so that this tank is very slowly filled, the constant flow of water being very small.

It is evident that various changes, modifications and variations might be resorted

to without departing from the spirit and 65 scope of my invention and hence I do not wish to limit myself to the exact disclosure hereof, but consider myself entitled to all such variations and departures as involve the definitions of the following claims. 70

What I claim is:

1. Apparatus for maintaining negative pressure in advance of the heating fluid in fluid house heating systems, comprising a closed liquid drainage passage, means for 75 supplying liquid thereto, and means for automatically forming bodies of water at successive points along said passage and causing them to descend in succession therein to exert separate air exhausting actions 80 therein, substantially as described.

2. In a fluid house heating system, apparatus for maintaining negative pressure pull in the system in front of the heating fluid therein, comprising a vertical series of successive closed liquid chambers, means whereby air-exhausting columns of liquid are caused to successively descend from chamber to chamber, and means for supplying liquid to the top chamber of the 90 series.

3. Apparatus for exhausting dead air from fluid house heating systems, comprising a series of drain pipes, and means for forming the same body of liquid into columns of liquid to successively descend through said pipes, substantially as 95 described.

4. Apparatus for maintaining negative pressure pull on the heating fluid in fluid 100 heating systems, comprising a series of tanks arranged at different elevations, connections for draining the liquid from each tank to the next tank below to thereby exert successive air exhausting actions, and 105 a source of liquid supply, substantially as described.

5. Apparatus for maintaining minus pressure pull on the radiator systems of fluid heating plants, characterized by a series of 110 chambers having air exhausting connections with the radiating systems, a source of liquid supply, and a series of devices constructed and arranged for successively and automatically filling and draining liquid 115 from said chambers for successively forcing air from and drawing air into said chambers, substantially as described.

6. In a fluid house heating system, in combination, radiators, and means for 120 maintaining minus pressure pull on the radiators of the system, said means comprising a vertical series of closed chambers each having an air offtake passage and each having an air inlet passage connected with said radiators to exert minus pressure pull on the interiors thereof, and connections for supplying water into the uppermost cham-

ber and for successively filling and emptying said chambers, substantially as described.

7. Apparatus for maintaining minus pressure full in a fluid heating system, comprising an air line having an air discharge to atmosphere, said air line including a vertical series of closed chambers each having a valved air inlet and a valved air outlet, means for supplying liquid for filling the uppermost chamber of said series, and drain pipes connecting said chambers for successively draining the liquid from said uppermost chamber and filling and emptying the chambers below and finally discharging the water from the lowermost chamber.

8. A steam or vapor heating system comprising radiators, a closed air pipe line from the discharge ends of the radiators leading to, and provided with, an air discharge for the free discharge of air from said line but closed against back flow of fluid to the line, and means comprising a series of connected closed liquid chambers included in said line for successively acting to produce minus pressure therein by the passage of liquid from chamber to chamber.

9. In a steam or vapor heating system, a radiator, an elongated vent pipe, in open communication with said radiator, a fluid seal to prevent back flow of outside air through said pipe, and means in closed communication with both the radiator and pipe and involving liquid chambers and devices controlling the discharge of liquid therefrom.

10. A vapor or steam heating system comprising a radiator, and elongated vent pipe, a fluid seal to prevent back flow of air in said pipe, a check valve to prevent fluid from said seal rising in said pipe, and connected liquid chambers having drainage devices to draw air from said radiator and to expel air into said vent pipe.

45 11. A vapor or steam heating system comprising a radiator, an elongated vent pipe having a discharge to atmosphere provided with means to prevent back flow, a thermostatic valve to prevent flow of steam from the radiator, and means to draw air from the radiator and to expel air into the vent pipe embodying devices for successively draining a body of liquid from one closed chamber to another.

55 12. A steam or vapor heating system comprising radiators, a pipe line for drawing air from the radiators, said pipe line having a discharge for the free discharge therefrom of the air drawn from the radiators, and means for producing and maintaining minus pressure in said pipe line by the drainage of stored water from one closed chamber to another of a series of such chambers.

65 13. A steam or vapor heating system comprising a radiator having an air discharge

pipe with a vertical portion terminating at its lower end in an air discharge provided with a liquid seal, and means for drawing air from said radiator and expelling the same into said discharge pipe embodying several liquid chambers and connecting drainage devices.

14. A steam or vapor heating system comprising radiators, a pipe line connected with the radiators to receive the dead air therefrom and having an air discharge to the atmosphere and embodying a water and air storage chamber provided with means for draining the water therefrom for the purpose of exhausting air from the radiators, and a series of tanks receiving the water from said chamber and successively filled and emptied thereby.

15. Apparatus for removing air in front of the heating fluid in steam, vapor and other fluid heating systems, comprising a storage liquid tank to receive air from the system, means for supplying liquid to said tank, a series of closed liquid chambers connected to receive air from the system and to discharge air therefrom, and drainage devices for periodically and successively filling and emptying said chambers and for periodically discharging liquid from said tank to supply said chambers.

16. In a fluid heating plant radiator system, in combination, a storage tank communicating with the radiators to receive the dead air therefrom provided with an air vent sealed against inlet of air, means for filling the tank with water to discharge the stored air therefrom through said vent, and a series of closed chambers connected to receive the drainage from said tank and connected together to drain from one to the other and having air outlets and connected with the radiators to draw air therefrom.

17. Apparatus for maintaining an air exhausting action on the radiator systems of fluid heating plants, comprising a vertically-disposed closed liquid passage embodying a series of chambers and means for causing a column of liquid to descend through said passage from chamber to chamber.

18. Apparatus for withdrawing air from the radiator systems of fluid heating plants to compensate for air leakage, comprising an upright liquid passage embodying a succession of air exhausting and discharging stages, and means for causing an air exhausting and discharging body of liquid to descend through said passage from stage to stage.

19. Apparatus for withdrawing air from fluid heating plant radiators, comprising several closed chambers at different elevations, and means for causing a column of liquid to pass down through said chambers successively, substantially as described.

20. Apparatus for withdrawing air from

fluid heating plant radiator systems and the like, comprising a closed passage, means for causing a body of liquid to descend in said passage, and a succession of devices whereby 5 said body of liquid is caused to exert a succession of air withdrawing and discharging operations while descending through said passage.

21. Apparatus for maintaining an air 10 exhausting action on the radiator system of a fluid heating plant, and for expelling the dead air by utilizing the pressure reducing action of a descending body of liquid, said apparatus comprising several closed chambers, devices including automatic valve mechanisms for periodically filling and emptying said chambers in succession, and means for providing a small constant flow of liquid into the first chamber of the series. 15

22. Apparatus for drawing air from the radiator system of a fluid heating plant, and for expelling said air comprising a series of closed chambers, each chamber having an air outlet and being connected with the 20 radiator system, and a liquid supply tank from which liquid is drained into the first chamber of said series.

23. A steam heating system provided with means for exhausting air from the radiators 30 of the system and for expelling said air comprising a drainage system wherein liquid is successively drained from one closed chamber to another of a series of such chambers to successively fill said chambers to expel 35 air therefrom and to empty said chambers to produce air exhausting action on said radiators.

24. A steam heating system provided with means for exhausting air from the radiators 40 of the system and for expelling said air comprising a liquid tank having a small constantly running liquid supply and an automatic valve controlled drainage device for maintaining the outlet from the tank 45 closed while the tank is filling and the air is being expelled therefrom and for automatically draining the liquid from said tank to draw air thereinto, after said tank has been filled, and then for automatically 50 closing said outlet so that the tank can be refilled.

25. Apparatus for exerting negative pressure pull on the heating fluid in house heating systems, comprising a vertical series 55 of liquid tanks, means to supply a charge of liquid to the upper tank, and air exhausting connections from each tank to the heating system, each tank provided with an outlet and drainage pipe to a tank below, 60 said outlet being provided with an automatic valve mechanism whereby the outlet is closed as soon as the tank is emptied and is maintained closed until the tank is filled and is then automatically opened so that 65 the tank can be drained through said pipe.

26. In a steam heating system, a tank provided with a bottom well, an air vent from said well to the upper portion of the interior of the tank, said vent serving as an overflow from the tank to the well, a bottom discharge being provided from the tank to the well, a vertically movable valve in said tank for closing and opening said discharge and provided with buoyant means for unseating the same, and a drainage pipe 70 for carrying off the liquid from said well. 75

27. In a steam heating system, a closed tank provided with a well into which the liquid from the tank drains, said tank having a discharge port into the well, a vertically movable valve in the tank for closing said port automatically when the tank has been emptied and for automatically opening said port when the tank has been filled with liquid, and a drainage pipe from said well 80 at its upper end having a goose neck in said well whereby said pipe constitutes a siphon. 85

28. Apparatus for drawing air from the radiator system of a fluid heating plant, 90 characterized by a series of chambers having air exhausting connection with the radiator system, a source of liquid supply, and a series of devices constructed and arranged for successively and automatically filling 95 and draining liquid from said chambers for successively forcing air from and drawing air into said chambers, substantially as described.

29. Apparatus for maintaining negative 100 pressure in advance of the heating fluid in fluid house heating systems comprising a closed liquid drainage passage, means for supplying liquid thereto, and means for automatically forming bodies of water at successive points along said passage and causing them to descend in succession therein so as to draw the air in said passage downwardly through the same behind said descending bodies of water to exert air 110 exhausting action throughout the said passage, substantially as described.

30. In a fluid house heating system, apparatus for maintaining a vacuum in the system in front of the heating fluid there- 115 in, comprising a series of successive closed liquid chambers at different levels, means whereby air exhausting columns of liquid are caused to successively descend from chamber to chamber and drive the air in 120 said chambers successively downward from chamber to chamber, and means for supplying liquid to the top chamber of the series.

31. Apparatus for exhausting dead air 125 from fluid house heating systems comprising a drain pipe, and means for forming the same body of liquid into columns of liquid to successively descend through said pipe, substantially as described. 130

32. A steam heating system provided with means for exhausting air from the radiators of the system and for expelling said air, comprising a liquid tank having a constantly running liquid supply and an automatic valve controlled draining device for closing the outlet from the tank when the latter begins to fill and the air is being expelled therefrom, and for automatically draining the liquid from said tank to draw air thereinto, after said tank has partially emptied.

5 at different levels, means to supply a charge of liquid to the upper tank, and air exhausting connections from each tank to the next upper tank and finally to the heating system forming drainage outlets from each tank to the next lower tank and finally to the atmosphere, said outlets being provided with automatic valve mechanism whereby the outlet is closed after the tank is drained and commences to refill, and is automatically opened after the tank is filled and has partially emptied to complete the drainage of said tank.
